UNITED STATES PATENT OFFICE.

LARS LARSON, OF CHICAGO, ILLINOIS, ASSIGNOR OF ONE-FOURTH TO GEORGE PAULSON, OF CHICAGO, ILLINOIS.

SLAG-DISINTEGRATING APPARATUS.

1,184,462.

Specification of Letters Patent. Patented May 23, 1916.

Application filed February 8, 1915. Serial No. 6,765.

To all whom it may concern:

Be it known that I, LARS LARSON, a citizen of the United States, and a resident of the city of Chicago, county of Cook, and 5 State of Illinois, have invented certain new and useful Improvements in Slag-Disintegrating Apparatus, of which the following is a specification.

My invention relates to improvements in 10 slag disintegrating apparatus, and has for its object the production of mechanism of this character which will be of improved construction and efficient in operation.

A further object is the production of slag 15 disintegrating apparatus in which the cooling of the slag before disintegration will be effected without the necessity of subjecting the molten slag to the direct action of water.

Other objects will appear hereinafter.

20 The invention consists in the combinations and arrangements of parts hereinafter described and claimed.

The invention will be best understood by reference to the accompanying drawings 25 forming a part of this specification, and in which—

Figure 1 is a side elevation of a slag disintegrating apparatus embodying my invention, Fig. 2 is a top plan view of the same, 30 Fig. 3 is a section taken on substantially line $x-x$ of Fig. 1, Fig. 4 is an enlarged central vertical section of one end of the apparatus, and Fig. 5 is an enlarged detail section taken on line $y-y$ of Fig. 4.

35 The preferred form of construction, as illustrated in the drawings, comprises a reservoir 1 into which the molten slag to be treated is deposited. The reservoir 1 is provided at its front end with an outlet opening 40 2 which is controlled by a vertically slideable gate valve 3 which is mounted between guide flanges 4 provided upon the front wall of said reservoir. The front end of the reservoir is reduced at the approach thereof to 45 the discharge opening 2. The gate valve 3 is manually controlled by means of a stem 5, the lower end of which is loosely rotatable in a bearing provided upon the front side of said valve, the upper end of said stem being 50 threaded in a member 6 secured to the upper edge of the reservoir. At the upper end of stem 5 is provided a hand wheel 7 whereby

said stem may be rotated for moving the valve 3 as desired.

Arranged below the front end of the reservoir 1 is the rearward end of an elongated tank 8 which is suitably supported upon supporting frame work, as shown. Rotatably mounted in the respective ends of tank 8 are shafts 9 and 10 upon which are 55 mounted pairs of spaced sprocket wheels 11 and 12 respectively. The shaft 10 is projected at one end for the accommodation of a pulley 13, as clearly shown in Fig. 2, through the medium of which connection 60 may be made for driving the same. Mounted for travel around the sprocket wheels 11 and 12 are two spaced endless sprocket chains 14.

Arranged upon the inner sides of the lateral walls of tank 8 are inwardly projecting angle irons 15 for engagement with the under sides of chains 14 to support the same in the travel of said chains, as will be readily understood.

Arranged between the chains 14 is a plurality of flat rectangular plates 16 arranged edge to edge, the lateral edges of said plates having upwardly turned flanges 16' which are fastened to said chains, as shown. Reinforcing angle irons 17 are provided at the 80 under sides of plates 16 to prevent warping or sagging of said plates, as will be readily understood. Provided at the front edge of each plate 16 is a downwardly offset flange or lip 18 adapted to overlap with or engage 85 under the rearward edge of the next forward plate, as clearly shown in Fig. 4, in order to maintain said plates in proper alignment and prevent the forward edge of any of said plates projecting above the rearward edge of the next forward plate, the reason for this precaution being hereinafter set forth as will appear. The arrangement is such, as will be seen, that an elongated longitudinally movable endless platform is 90 constituted by the chains 14 and the members 16 which, when the apparatus is in use, passes immediately below the outlet opening 95 of the reservoir 1.

Arranged below the upper portion of the 100 endless platform immediately forward of the outlet opening of the reservoir 1 is a spraying nozzle 19 which is constituted by a substantially U-shaped pipe having open-

ings at its upper side through which the cooling liquid supplied to said pipe is adapted to pass in the form of a great number of small streams or sprays for contacting with the under sides of plates 16 in order to cool the same. The nozzle 19 is connected at one end with a supply pipe 20 which leads to any suitable source of cold water supply. Passage through the pipe 20 is controlled 1 by a suitable valve 21.

Arranged at the forward end of the tank 8 or above the shaft 10 is a centrally positioned longitudinally extending trough 22 which is suitably rigidly supported. The 15 trough 22 is of less width than said tank or the plate 16, as shown in Fig. 2. Hinged at 23 to one end of the bottom of the trough 22 is a plate 24 so arranged that the outer or free end thereof rests loosely upon 20 the upper side of the traveling platform, that is the plates 16. In order to insure a close engagement between the upper sides of said plates and the front edge of said plate 24, the under side of said edge of said plate 25 it beveled, as clearly shown in Fig. 4. Also arranged at the entrance end of the trough 22 are divergent laterally projecting plates 25 secured, by means of bolts 26 and co-operating nuts, to supporting plates 27 30 rigidly secured to suitable adjacent supporting structure. The bolts 26 engage vertically extending elongated slots 28 formed in the plates 25, as clearly shown in Fig. 5, which permit of vertical adjustment of said 35 plates in order to adjust the lower edges thereof relative to the upper side of the platform.

In the operation of the apparatus, the slag which is deposited upon the platform from 40 the outlet opening of the reservoir 1 will be cooled by reason of the cooling of the plates 16 through spraying thereof by the nozzle 19. As the cooled and therefore hardened slag reaches the plates 24 and 25, the same 45 will be scraped thereby from the upper side of the platform and directed toward the entrance end or mouth of trough 22. In order to insure the thorough scraping of the platform by the plates 25, the lower edges of the 50 latter are bent forwardly at an angle, as clearly shown in Fig. 5, said bending of said edge rendering the removal of the slag from the platform more easy and with less resistance. Through the provision of the 55 lips 18 at the front edges of platform plates 16, the possibility of engagement of said edges of said plates with the scraper plates 24 and 25 is precluded since, as above pointed out, with this construction it is impossible for said edges of said plates to project 60 above the rearward edges of the next forward plates. Arranged above the respective ends of trough 22 are shafts 29 and 30 upon which are mounted pairs of spaced sprocket 65 wheels 31 and 32 respectively. Traveling

around the sprocket wheels 31 and 32 are two spaced sprocket chains 33 upon which are carried scraper members or buckets 34 adapted, upon movement of the chains 33 to successively enter and travel along the 70 trough 22 in order to carry the slag directed therein by the plates 24 and 25 to the rearward open end of said trough. The buckets 34 are preferably of less width than the trough 22, the front edges of the lateral 75 walls of said buckets being, however, bent outwardly into close proximity with the lateral walls of said trough, as clearly shown in Fig. 2. This arrangement is adopted in order to prevent particles of slag being 80 caught between the sides of the buckets and the adjacent lateral walls of the trough and thus interfere with the free passage of said buckets through the trough. The shaft 30 is extended at one end to accommodate a 85 pulley 37 through which attachment may be made to a source of power for driving of said shaft, as will be readily understood. The slag which is carried rearwardly in the trough 22 by the buckets 35 when carried 90 beyond the rearward end of said trough drops therefrom into a hopper 38 arranged below said end of said trough, as clearly shown in the several views. Arranged at the lower end of said hopper are disintegrating 95 rollers 39 through the medium of which the slag, which is deposited into said hopper will be crushed or granulated to the desired degree of fineness, as will be readily understood. The endless platform is of such 100 length that there is considerable slack in the under portion thereof so that after passing around the sprocket wheels 12, the same dips downwardly into a compartment 8' which is constituted at the bottom of the tank 8. 105 This compartment in the operation of the apparatus is supplied with cooling water and therefore in the passage of the platform through said compartment, said platform will be subjected to a bath to effect cooling 110 of the same. An over-flow pipe 40 is provided in the side of compartment 8' for determining the level of the cooling water contained therein and a drain pipe 41 registers with the bottom of said compartment for 115 entirely draining the same when desired in order to remove any sediment which may gather therein.

In order to insure against the lodging of any particles of slag or foreign matter upon 120 the lips or flanges 18 so as to thus prevent proper seating of the rearward edges of the next forward plates against said lips, a nozzle 42 is provided at the rearward end 125 of the tank 8 adjacent the sprocket wheels 11. The nozzle 42 is so positioned as to be adapted to direct a spray of water transversely of the plates 16 and into engagement with the outer side of each lip or flange 18 as the same passes said nozzle and thus serve 130

to effectively clean the joints between the plates before the same are closed which occurs immediately after said plates pass from engagement with the sprocket wheels 11. 5 The nozzle 42 is supplied with water through a pipe 43 which connects with the supply pipe 20. The arrangement is such, as will be seen, that the valve 21 serves as a control for both nozzles 19 and 42. The water which is 10 discharged from said nozzles drips down the sides of the tank 8, accumulating in the cooling compartment 8' which is thus supplied with the water for cooling at this point, as above described. The bottom of the tank 8 15 is inclined in both directions toward the compartment 8' so that the water will readily drain into the latter.

While I have illustrated and described the preferred form of construction for carrying 20 my invention into effect, this is capable of variation and modification without departing from the spirit of the invention. I, therefore, do not wish to be limited to the precise details of construction set forth, but 25 desire to avail myself of such variations and modifications as come within the scope of the appended claims.

Having described my invention what I 30 claim as new and desire to secure by Letters Patent is:

1. Apparatus of the class described comprising two spaced rotatable elements; a longitudinally movable endless platform mounted for travel around said elements, said platform 35 comprising a plurality of overlapping flexibly connected sections; scraping means arranged for coöperation with said platform; and means for cleaning the joints between said sections, substantially as described.

2. Apparatus of the class described comprising two spaced rotatable elements; a longitudinally movable endless platform mounted for travel around said elements, 45 said platform comprising a plurality of overlapping flexibly connected sections; scraping means arranged for coöperation with said platform; and means for cleaning the joints between said sections as said sections pass around one of said rotatable elements, substantially as described.

3. Apparatus of the class described comprising two spaced rotatable elements; a longitudinally movable endless platform 55 mounted for travel around said elements, said platform comprising a plurality of overlapping flexibly connected sections; scraping means arranged for coöperation with said platform; and a fluid nozzle for spraying the joints between said sections to remove foreign matter therefrom as said sections pass around one of said rotatable elements, substantially as described.

4. Apparatus of the class described comprising an elongated tank; two spaced rota-

table elements arranged at the ends of said tank; a longitudinally movable endless flexible platform mounted for travel around said elements, said platform consisting of a plurality of flexibly connected flat sections arranged edge to edge; a fluid spraying nozzle for spraying the joints between said sections to remove foreign matter therefrom as said sections pass around one of said rotatable elements; a nozzle for spraying cooling fluid 70 against the under side of the upper portion of said platform; and a compartment provided at the bottom of said tank into which the lower portion of said platform is adapted to dip in the movement of the latter, the spray 75 from said nozzles draining into said compartment, substantially as described.

5. Apparatus of the class described comprising an elongated tank; two spaced rotatable elements arranged at the ends of 80 said tank; a longitudinally movable endless flexible platform mounted for travel around said elements, said platform consisting of a plurality of flexibly connected flat sections arranged edge to edge; a fluid spraying 85 nozzle for spraying the joints between said sections to remove foreign matter therefrom as said sections pass around one of said rotatable elements; a nozzle for spraying cooling fluid against the under side of the 90 upper portion of said platform; and a compartment provided at the bottom of said tank into which the lower portion of said platform is adapted to dip in the movement of the latter, the spray from said nozzles 95 draining into said compartment, there being an overflow opening in the side of said tank for determining the level of the fluid in said compartment, substantially as described.

6. Apparatus of the class described comprising an elongated tank; two spaced rotatable elements arranged at the ends of said tank; a longitudinally movable endless flexible platform mounted for travel around 100 said elements, said platform consisting of a plurality of flexibly connected flat sections arranged edge to edge; a fluid spraying nozzle for spraying the joints between said sections to remove foreign matter therefrom as said sections pass around one of said rotatable elements; a nozzle for spraying 110 cooling fluid against the under side of the upper portion of said platform; a compartment provided at the bottom of said tank into which the lower portion of said platform is adapted to dip in the movement of the latter, the spray from said nozzles 115 draining into said compartment; and a valve for controlling the supply of fluid to 120 said nozzles, substantially as described.

7. Apparatus of the class described comprising an elongated longitudinally movable platform; scraping means coöperating with said platform, said scraping means 130

- comprising a trough arranged above said platform; and inclined means at the front end of said trough adapted to engage against the upper side of said platform to 5 remove the substance contained thereon and direct the same into said trough, substantially as described.
8. Apparatus of the class described comprising an elongated longitudinally movable platform; slag removing means coöperating with said platform, said means comprising a receptacle arranged above said platform and open at its front end; and an inclined plate hinged to the front end of 10 said receptacle, the free end of said plate being adapted to rest against the upper side of said platform to scrape the substance contained thereon and direct the same into said receptacle, substantially as described.
- 15 9. Apparatus of the class described comprising an elongated tank; an elongated longitudinally movable platform arranged in said tank; slag removing means coöperating with said platform, said means comprising a receptacle arranged above said platform and open at its front end, said receptacle being narrower than said tank; a downwardly inclined member at the front end of the bottom of said receptacle; and 20 laterally projecting divergent plates extending from the sides of said receptacle adapted to engage against the upper side of the platform to remove the substance contained thereon and direct the same into said receptacle, substantially as described.
- 25 10. Apparatus of the class described comprising an elongated tank; an elongated longitudinally movable platform arranged in said tank; slag removing means coöperating with said platform, said means comprising a receptacle arranged above said platform and open at its front end, said receptacle being narrower than said tank; a downwardly inclined member at the front end of the bottom 30 of said receptacle; and laterally projecting vertically adjustable divergent plates extending from the sides of said receptacle adapted to engage against the upper side of said platform to remove the substance contained thereon and direct the same into said receptacle, substantially as described.
- 35 11. Apparatus of the class described comprising an elongated tank; an elongated longitudinally movable platform arranged in said tank; slag removing means coöperating with said platform, said means comprising a receptacle arranged above said platform and open at its front end, said receptacle being narrower than said tank; a downwardly inclined member at the front end of the bottom 40 of said receptacle; laterally projecting vertically adjustable divergent plates extending from the sides of said receptacle adapted to engage against the upper side of said platform to remove the substance contained thereon and direct the same into said receptacle, substantially as described.
- 45 12. Apparatus of the class described comprising an elongated longitudinally movable platform; slag removing means coöperating with said platform for removing the slag contained thereon, said slag removing means comprising a trough arranged above said platform, said trough being open at both ends; means at the front end of said trough for scraping the substance contained on said platform and directing the same into the front end of the trough; members mounted for movement longitudinally of said trough for carrying the substance entering the front end thereof rearwardly in said trough and discharging the same from the rearward end thereof; and disintegrating mechanism arranged below the rearward end of said trough, substantially as described.
- 50 13. Apparatus of the class described comprising an elongated longitudinally movable platform; slag removing means coöperating with said platform for removing the slag contained thereon, said slag removing means comprising a trough arranged above said platform, said trough being open at both ends; means at the front end of said trough for scraping the substance contained on said platform and directing the same into the front end of the trough; a plurality of buckets mounted for movement longitudinally of said trough for carrying the substance entering the front end thereof rearwardly in said trough and discharging the same from the rearward end thereof; and disintegrating mechanism arranged below the rearward end of said trough, substantially as described.
- 55 14. Apparatus of the class described comprising an elongated longitudinally movable platform; slag removing means coöperating with said platform for removing the slag contained thereon, said slag removing means comprising a trough arranged above said platform, said trough being open at both ends; means at the front end of said trough for scraping the substance contained on said platform and directing the same into the front end of the trough; members mounted for movement longitudinally of said trough for carrying the substance entering the front end thereof rearwardly in said trough and discharging the same from the rearward end thereof; a hopper below the rearward end of said trough; and disintegrating mechanism provided at the bottom of said hopper, substantially as described.
- 60 15. Apparatus of the class described comprising an elongated longitudinally movable platform; slag removing means coöperating with said platform for removing the slag contained thereon, said slag removing means

comprising a trough arranged above said platform, said trough being open at both ends; means at the front end of said trough for scraping the substance contained on said platform and directing the same into the front end of the trough; members mounted for movement longitudinally of said trough for carrying the substance entering the front end thereof rearwardly in said trough and 10 discharging the same from the rearward end thereof; a hopper below the rearward end of

said trough; and disintegrating rollers provided at the bottom of said hopper, substantially as described.

In testimony whereof I have signed my 15 name to this specification in the presence of two subscribing witnesses.

LARS LARSON.
